UNITED STATES PATENT OFFICE.

JOHN ZELLWEGER, OF LOUISVILLE, KENTUCKY.

IMPROVEMENT IN BRIDGE-COLUMNS.

Specification forming part of Letters Patent No. 145,545, dated December 16, 1873; application filed October 20, 1873.

To all whom it may concern:

Be it known that I, JOHN ZELLWEGER, of Louisville, in the county of Jefferson and State of Kentucky, have invented certain Improvements in Bridge-Posts, of which the following is a specification:

My invention relates to the construction of bridge posts, braces, or columns. I connect rigidly the several members or main bars for a post or brace by means of one or more bars of metal, called "truss-bars," bent in such a manner around a central axis as to form either curved, screw-shaped, or winding lines, similar to the windings of the threads of a screw, or so as to form angular winding lines, either with equal or unequal straight parts, similar to winding stairs built of straight sections.

In trussed braces or posts as hitherto designed or built, the main bars are either connected by zigzag-shaped truss-bars, or by a number of short straight bars, arranged in oblique positions between the main bars, with which they form a series of triangles. The zigzag-shaped truss-bar is made by bending a suitable bar, at nearly equidistant points, forward and backward alternately, which bending is done in one and the same plane, but in two different directions.

Trussed braces or posts with the new or winding truss-bars as connecting parts differ essentially from either of the two kinds of braces or posts just mentioned in the shape of the truss-bars, as said winding truss-bars are never straight for their entire length, but are bent, in one and the same direction, around a central axis, so as to form a kind of spiral line, which cannot be in one and the same plane.

The objects of the invention are, first, to allow of the construction of open posts or columns; second, to lessen the cost of manufacture of such posts; third, to make the trussed posts or braces more convenient for pin-connections.

Figure 1 is an elevation of an open post made out of four T-beams as main bars, riveted to a uniformly screw-shaped winding truss-bar, or spiral truss-bar. Fig. 2 is a top view of the same. Fig. 3 is an elevation of an open post made out of four angle-irons as main bars, riveted to an angular winding truss-bar. Fig. 4 is a top view of the same. Fig. 5 is a front el-

evation of a trussed brace with only two flat bars as main bars, riveted to the short sides of an angular winding truss-bar. The truss-bar, in this elevation, shows similar to an ordinary zigzag bar, although it is an angular-winding truss-bar. The trussed brace shown in this figure is tapering toward one end. Fig. 6 is a side elevation of the same with one main bar taken off. This elevation shows more plainly the manner in which the truss-bar is bent. Fig. 7 is a bottom view of the same.

Similar letters of reference indicate corresponding parts.

A, main bars; B, truss-bars; C, end rings; D, pin.

The main bars or members of a built post or brace may be held together by one or more winding truss-bars. If there is more than one, they can be wound in the same or in different directions. In the latter case it would be of advantage to rivet the truss-bars together at their intersections. The main bars may be secured to the truss-bars by one or more rivets or bolts at each intersection. The several windings of the truss-bars may be equal in size from end to end of the post or brace; or they may become smaller or larger, either from one end toward the other end, or from the center toward the ends.

Since the winding truss-bar of a brace or post is, in all its points, some distance away from its axis, it is practicable to run a pin centrally through the main bars without interfering with the truss-bar—a feature very desirable in many cases.

By the use of a winding truss-bar as a connecting part between the main bars of a built post or brace, it is possible to construct an "open post" or "open brace" the interior of which can be conveniently inspected and painted.

In some cases the truss-bars may be outside of the main bars. The windings of a truss-bar may be terminated by bending it at right angles to the central axis of the post or brace.

In some cases a ring or an angular band would do good service to keep the ends of the main bars in their relative positions. Flat plates or rings or angular bands of sufficient width may be secured to the main bars to facilitate pin-connections.

The winding truss-bars can conveniently be made by winding suitable bars around properly-shaped pattern-beams. The metal strap for the truss-bar may be heated in a furnace of suitable length, and then pulled out by winding it over the pattern-beams, which would have to revolve around their longitudinal axis, and, at the same time, be in motion along said axis.

It would be advantageous to take the bars directly from the rolls between which they were made, and bend them over the pattern-beams without reheating.

In connection with the winding up of the truss-bars they will have to be hammered or pressed to a close fit around the pattern-beams, in which operation the contraction of the bars while cooling off can be successfully made use of.

The pattern around which the truss-bars have to be wound may consist either of one suitably-shaped beam, called a "pattern-beam," or of two or more such beams. In the latter case the pattern-beams have to be set at any desired distance apart, and at any divergence or inclination toward each other by means of struts, stay-bolts, or wedges. On the outside of the pattern-beams suitable keys or saddles may be mounted, over which to wind the truss-bars. By this arrangement the finished truss-bars could be readily removed from the patterns.

If the pattern has only one beam, the use of saddles would be of special advantage, as it would only be necessary to employ saddles or

keys of various sizes and shapes to make the windings of the truss-bars of any desired size and shape. A pattern with one single beam, upon which various saddles or keys can be mounted and secured, has the great advantage of being simpler and less liable to get out of order than one with two or more pattern-beams. Said keys or saddles could be made to answer as punch-blocks, on which to punch the necessary holes in the truss-bars. After the punching of these holes the main bars might be secured in their proper places before removing the truss-bars from the pattern-beams. The truss-bar, when being wound up, may have to go through between two rollers for the purpose of being stretched.

The pattern-beams may be mounted on tables or frames, which would have to run longitudinally on slides, rollers, or small wheels, similar to the carriages in saw-mills.

The rotary motion of the pattern-beams may be obtained, through suitable gearings, from the longitudinal motion of the carriages.

I claim as my invention—

The rigid connection of the main bars A of a built post, brace, or column by means of curved or angular winding truss-bars B, substantially as described.

JOHN ZELLWEGER.
